ATTORNEY

UNITED STATES PATENT OFFICE.

WILLIAM W. HAYDEN, OF NEWARK, NEW JERSEY.

DESIGN FOR A HANDLE FOR CUTLERY, &c.

SPECIFICATION forming part of Design No. 21,809, dated August 30, 1892.

Application filed July 20, 1892. Serial No. 440,677. Term of patent 3½ years.

To all whom it may concern:

Be it known that I, WILLIAM W. HAYDEN, a citizen of the United States, and a resident of Newark, in the county of Essex and State of New Jersey, have invented and produced a certain new and original Design for a Handle for Cutlery, of which the following is a specification.

The accompanying drawing, forming a part of this specification, and to which reference is made, illustrates my newly-designed handle for cutlery and other articles.

My new design relates to the form and ornamentation of the handle; and the leading feature consists of marginal relief-work and scrollwork reaching from the curves of the handle upon or across the body thereof. The handle A displays at its margins or edges the outward swells or curves a a, b b, and c c, which latter form the rounded corners or end of the handle and join the small central end

projection or knob d. The edges also display the inward curves e e, f f, and g g, and at the edges appears the rounded relief-work h h, which curves around the sides of the handle. 25 At the point of the handle appears a scroll i, which joins an oppositely-curved scroll i'. At or near the center of the handle appears the foliated ornament j, which reaches diagonally across the handle and comprises the two 30 scrolls j' j''. Adjacent to the ornament j appears a double scroll k, and at the end of the handle appears a leaf ornament l, springing from two spirals l'.

What I claim is—

The design for a handle for cutlery, substantially as herein shown and described.
